TOP FEEDING MECHANISM FOR BLIND STITCH SEWING MACHINES

Ralph S. Kelso, St. Louis, Mo., assignor to Lewis Invisible Stitch Machine Company, St. Louis, Mo., a corporation of Maine

Application November 6, 1936, Serial No. 109,595

4 Claims. (Cl. 112—212)

This invention relates to new and useful improvements in top feeding mechanism for blind stitch sewing machines.

Among the several objects of the invention are to provide a 4-motion top feed mechanism housed within a forwardly extending stitching arm of a blind stitch sewing machine; to provide means for varying the feed stroke of the feed dog, and to provide such a mechanism which is extremely simple in construction and durable in operation.

With these and other objects in view which will more fully appear, the nature of the invention will be more clearly understood by following the description, the appended claims, and the several views illustrated in the accompanying drawings.

In the drawings:—

Figure 1 is a side elevation of a stitching arm showing the application of my invention,

Figure 2 is a bottom plan view thereof,

Figure 3 is a partial rear elevation thereof, the frame arm being shown in section,

Figure 4 is a detail elevation of the feeding mechanism, the view showing particularly the means for imparting up and down movements to the feed dog, and

Figure 5 is a detail elevation showing particularly the means for imparting the backward and forward movements to the feed dog.

Like reference numerals designate corresponding parts throughout the several figures of the drawings.

The sewing machine frame A to which my invention has been applied, includes a forwardly extending hollow stitching arm 5 having a horizontal presser foot 6 rigidly secured to the free end thereof and provided with a longitudinal opening 7. Journaled in the main frame and projecting transversely across the arm 5 at the end thereof opposite the foot 6, is a main or drive shaft 8. Journaled in the arm 5 and extending longitudinally thereof is an oscillatory needle shaft 9 which is driven from the main shaft by a connection indicated generally at 10. The needle shaft is disposed above the foot and fixed to the forward end thereof is a needle arm 11 carrying a curved needle 12, the needle thus being reciprocated across the slot 7 in the foot 6. Any suitable means (not shown) may be provided for projecting nodes of fabrics upwardly through the slot 7 into needle penetrating position.

In order to feed the fabrics up to and past the needle, I have provided a 4-motion top feeding mechanism within the frame arm 5. This mechanism includes a feed dog 13 having a front feed section 14 and a rearwardly spaced feed section

15, said sections being connected by a longitudinally extending bridge 16 forming a resultant opening 17 thereunder. This feed dog 13 is attached to a feed bar 18 by screws 19. The feed sections operate in the opening 17 of the presser foot and against the usual upwardly spring pressed work clamp, the front section 14 being located in front of the needle path and the rear section 15 in rear of said path. The feed bar 18 is raised and lowered by a train of mechanism 10 from the main shaft 8, and is moved back and forth by a train of mechanism operated from said main shaft. A bell crank lever 20 is pivoted at its angle as at 21 to the forwardly extending arm 5 of the frame. This bell crank lever includes a 15 forwardly extending arm 22 and a downwardly extending arm 23. A link 24 is pivotally connected at its upper end as at 25 to the arm 22 and at its lower end as at 26 to the feed bar 18. The rear end of the feed bar is provided with an inclined open ended slot 27 which has sliding connection on a bearing pin 28 fixed to the forwardly extending frame arm 5. A pitman 29 is pivotally connected at its forward end as at 30 to the depending arm 23 of the bell crank lever 20 and the rear end of this pitman is connected with an eccentric 31 fixed on the main shaft 8. It will thus be seen that upon rotation of the main shaft, the eccentric 31 will rock the bell crank lever 20 which, through the medium of the link 25, will raise and lower the feed bar 18. In order to move the feed bar back and forth, I have provided a slotted segment 32 which is pivoted at its upper end as at 33 to the forwardly extending frame arm 5. A driving link 34 is pivotally connected at its forward end as at 35 to the feed bar 18 and the rear end of this link is adjustably connected to the slotted segment 32 by a clamping bolt 36, the slot of the segment being arcuate and having for its center the pivot 35. The slotted segment 32 is pivotally connected as at 37 to a sleeve 38 which surrounds an eccentric 39 fixed on the main shaft 8. Thus upon rotation of the main shaft 8, the eccentric 39 will impart swinging movements to the slotted segment 32 and this segment through the medium of the link 34 will impart back and forth movements to the feed bar 18. By adjusting the clamping bolt 36 lengthwise of the slotted segment 32 the length of feed travel imparted to the feed dog 13 may be readily varied.

It is of course to be understood that the details of structure and arrangement of parts may be variously changed and modified without de-

45

parting from the spirit and scope of my invention.

I claim:

- 5 1. In a top feeding mechanism, the combination with a hollow frame arm, of a rotary shaft extending across one end thereof, a feed bar extending longitudinally within the arm, a feed dog fixed to the end of the bar opposite the shaft, the inner end of the bar having a sliding pivotal connection with the frame arm, means for imparting up and down movements to the feed bar including an eccentric fixed to said shaft, and separate means for imparting backward and forward movements to the feed bar including an 10 eccentric fixed to said shaft.
- 15 2. In a top feeding mechanism, the combination with a hollow frame arm, of a rotary shaft extending across one end thereof, a feed bar extending longitudinally within the arm, a feed dog fixed to the end of the bar opposite the shaft, the inner end of the bar having a sliding pivotal connection with the frame arm, means for imparting up and down movements to the feed bar comprising a bell crank lever located intermediate the ends of the feed bar and fulcrumed on the frame arm above the feed bar, said lever including horizontal and vertical arms, a supporting link connecting the horizontal arm and the feed bar, an eccentric fixed to the shaft, and a pitman connecting the eccentric and the vertical arm of the bell crank lever, and separate means for imparting backward and forward movements to the feed bar including an eccentric fixed to said shaft.
- 20 3. In a top feeding mechanism, the combination with a hollow frame arm, of a rotary shaft extending across one end thereof, a feed bar extending longitudinally within the arm, a feed dog fixed to the end of the bar opposite the shaft, the inner end of the bar having a sliding pivotal connection with the frame arm, means for imparting up and down movements to the feed bar comprising an arcuate segment located intermediate the shaft and the feed bar and pivoted at its upper end to the frame arm, an eccentric fixed to the shaft, a driving connection between the eccentric and the segment, and a link pivotally connected at one end to the feed bar and having an adjustable connection at its other end with said segment.
- 25 4. In a top feeding mechanism, the combination with a hollow frame arm, of a rotary shaft extending across one end thereof, a feed bar extending longitudinally within the arm, a feed dog fixed to the end of the bar opposite the shaft, the inner end of the bar having a sliding pivotal connection with the frame arm, means for imparting up and down movements to the feed bar comprising a bell crank lever located intermediate the ends of the feed bar and fulcrumed on the frame arm above the feed bar, said lever including horizontal and vertical arms, a supporting link connecting the horizontal arm and the feed bar, an eccentric fixed to the shaft, and a pitman connecting the eccentric and the vertical arm of the bell crank lever, and separate means for imparting backward and forward movements to the feed bar comprising an arcuate segment located intermediate the shaft and the feed bar and pivoted at its upper end to the frame arm, an eccentric fixed to the shaft, a driving connection between the eccentric and the segment, and a link pivotally connected at one end to the feed bar and having an adjustable connection at its other end with said segment.

the inner end of the bar having a sliding pivotal connection with the frame arm, means for imparting up and down movements to the feed bar including an eccentric fixed to said shaft, and separate means for imparting backward and forward movements to the feed bar comprising an arcuate segment located intermediate the shaft and the feed bar and pivoted at its upper end to the frame arm, an eccentric fixed to the shaft, a driving connection between the eccentric and the segment, and a link pivotally connected at one end to the feed bar and having an adjustable connection at its other end with said segment.

4. In a top feeding mechanism, the combination with a hollow frame arm, of a rotary shaft extending across one end thereof, a feed bar extending longitudinally within the arm, a feed dog fixed to the end of the bar opposite the shaft, the inner end of the bar having a sliding pivotal connection with the frame arm, means for imparting up and down movements to the feed bar comprising a bell crank lever located intermediate the ends of the feed bar and fulcrumed on the frame arm above the feed bar, said lever including horizontal and vertical arms, a supporting link connecting the horizontal arm and the feed bar, an eccentric fixed to the shaft, and a pitman connecting the eccentric and the vertical arm of the bell crank lever, and separate means for imparting backward and forward movements to the feed bar comprising an arcuate segment located intermediate the shaft and the feed bar and pivoted at its upper end to the frame arm, an eccentric fixed to the shaft, a driving connection between the eccentric and the segment, and a link pivotally connected at one end to the feed bar and having an adjustable connection at its other end with said segment.

RALPH S. KELSO.
